US0D1022816S

(12) **United States Design Patent** (10) Patent No.: **US D1,022,816 S**
(45) Date of Patent: ** Apr. 16, 2024

(54) **VEHICLE GRILLE**

(71) Applicant: **PACCAR Inc**, Bellevue, WA (US)

(72) Inventors: **Jonathan S. Duncan**, Seattle, WA (US); **Steven H. Hovind**, Renton, WA (US); **Scott D. Hite**, Pilot Point, TX (US); **Brent Johnson**, Denton, TX (US); **Tu H. Do**, Lewisville, TX (US); **Troy R. McCuller**, Corinth, TX (US)

(73) Assignee: **PACCAR Inc**, Bellevue, WA (US)

(**) Term: **15 Years**

(21) Appl. No.: **29/874,539**

(22) Filed: **Apr. 20, 2023**

Related U.S. Application Data

(62) Division of application No. 29/634,311, filed on Jan. 19, 2018, now Pat. No. Des. 988,204.

(57) **CLAIM**

The ornamental design for a vehicle grille, as shown and described.

DESCRIPTION

FIG. 1 is a perspective view of the vehicle grille, showing our new design.

FIG. 2 is a front view thereof.

FIG. 3 is a top view thereof; and,

FIG. 4 is a right side view thereof, the left side view being a mirror image.

The broken lines shown in the drawings depict portions of the vehicle grille that form no part of the claimed design.

1 Claim, 4 Drawing Sheets
